UNITED STATES PATENT OFFICE.

FRANK A. VATH, OF CHICAGO, ILLINOIS.

THERMOSTAT FOR JOURNAL-BEARINGS, &c.

No. 839,340.

Specification of Letters Patent.

Patented Dec. 25, 1906.

Application filed September 19, 1904. Serial No. 225,149.

To all whom it may concern:

Be it known that I, FRANK A. VATH, a citizen of the United States, and a resident of the city of Chicago, county of Cook, and State of Illinois, have invented certain new and useful Improvements in Thermostats for Journal-Bearings or the Like; and I do hereby declare that the following is a full, clear, and exact description of the same, reference being had to the accompanying drawing, and to the letters of reference marked thereon, which forms a part of this specification.

This invention relates to means for detecting excess heat in journal-bearings.

Heretofore much trouble and inconvenience and great expense from injured bearings and lost time have resulted from overheated journal-bearings due to friction. This expense and inconvenience can easily be avoided if the tendency to heat is discovered in due time. Ordinarily, however, though the utmost vigilance is exercised the first notice to the oilers or engineers is the odor of the burning oil or the failure of some part of the machine to operate.

The object of this invention is to afford automatic means whereby the tendency of one or any number of the journal-bearings to overheat is instantly announced to the operator.

A further object of the invention is to provide a cheap and simple device capable of ready adjustment to different degrees of heat and capable of being attached to any journal-bearing or other device likely to become heated with but slight cost.

The invention consists in the matters hereinafter described, and more fully pointed out and defined in the appended claims.

In the drawing, the figure is a transverse vertical section of a journal and bearing therefor provided with a device embodying my invention, parts of which are shown diagrammatically and others in elevation.

As shown in said drawing, A represents a journal and A' a bearing-box of any desired construction and the cap A² of which, as shown, is provided in the top thereof or at any convenient point with a threaded seat in which is secured a thermostat. Said thermostat, as shown, comprises a tube B, of any desired material, conveniently of metal, cut to the desired length and threaded at its lower end to engage in said seat in the cap A² and is tapped at its lower end to receive the screw-plug a. Fitting tightly in said tube B

and extending close to the screw-plug is a sleeve of any suitable insulating material c', having a small central bore therethrough and having each of its ends countersunk to afford a cup-like depression, that at the lower end of the sleeve together with the lower end of the tube above the screw-plug a affording a receptacle C, adapted to be filled with mercury, alcohol, or other material which expands uniformly when heated and which when heated fills the bore in said sleeve. Seated in the upper end of said tube B is an adjustable electrical conductor comprising a metallic wire d', which fits closely in and extends below an insulating covering D, of any suitable kind, which fits in the upper end of the tube B and is held in place by means of a set-screw d, and, if desired, may be graduated in degrees on its outer side to enable the device to be set for the maximum temperature permissible before alarm. The conductor d' extends below its insulation and into the bore of said sleeve c' and is of a length to permit a sufficient degree of adjustment in said tube to indicate the dangerous or warning temperatures. To the outer end of said conductor is engaged a lead conductor-wire E, which extends to an annunciator E', of any desired type, located at the engine-room or any point where it can be conveniently observed by an operator. Said annunciator is provided with a bell e or other means affording an audible signal as well as visible signals, and a battery E² is connected therewith by means of the lead-wire E³. The circuit is completed by grounding one of the battery-conductors or by connecting back with the machine, as preferred.

The operation is as follows: The thermostats are engaged upon the bearings at any convenient or desirable points and with the bulb extending into some metallic part of the bearing, and each is quickly influenced by change of temperature in its bearing. The core or sleeve c', of insulating material, prevents any external temperature affecting the thermostat. When the temperature of the bearing becomes high enough to expand the mercury or other expandable matter within the receptacle C to a point where it contacts with the conductor d', a circuit with the battery is formed which operates the annunciator, enabling the operator to know instantly by inspection the endangered bearing.

While I have shown the thermostat carried on the journal-cap A², it is obvious that it

may be carried at any convenient point and upon the journal itself, if preferred, and it may be used in connection with stationary machinery or vehicles, the rolling-stock of railroads, on steam and other vessels, and for many other purposes.

Inasmuch as I have described but one of many possible constructions embodying my invention, I do not purpose limiting this application otherwise than necessitated by the prior art, as obviously many details of construction may be varied without departing from the principles of my invention.

I claim as my invention—

15 1. The combination with a journal-bearing provided with an outwardly - opening seat therein of a tube engaged in said seat, a screw-plug fitted in and closing the inner end of said tube, an insulator in said tube provided with a central longitudinal bore and cored at each end, an expansible fluid in the lower end of said insulator, a longitudinally-adjustable insulator in the outer end of said tube, an electrical conductor therein project-

ing inwardly into said cored insulator, said cored upper end acting to guide the conductor into the central bore and means connected with said conductor acting to produce an alarm.

2. In a device of the class described the combination with a journal-bearing having a seat therein, of a tube engaged in said seat, a screw-plug in the lower end of said tube, an axially-bored insulator in said tube having its ends countersunk one of which forms a guide to the bore, a liquid - containing chamber beneath said insulator, a conductor in the top of said tube, means for adjusting said conductor longitudinally in the insulator and an annunciator electrically connected with said conductor.

In testimony whereof I have hereunto subscribed my name in the presence of two subscribing witnesses.

FRANK A. VATH.
